Primary Examiner — Ian Simmons*Assistant Examiner* — Keith Frank(74) *Attorney, Agent, or Firm* — James J. Cummings(57) **CLAIM**

The ornamental design for a bottle, as shown and described.

DESCRIPTION

FIG. 1 is a front perspective view of a bottle embodying my new design;

FIG. 2 is a front and back side elevation view thereof, the front and back side elevations being identical views;

FIG. 3 is a right and left side elevation view thereof, the left and right side elevations being identical views;

FIG. 4 is a top plan view thereof; and,

FIG. 5 is a bottom plan view thereof.

The broken lines are included for the purpose of illustrating the portions of the bottle that form no part of the claimed design.
